LIGHTER

Otto Reich, Vienna, Austria, assignor of one-half
to Julius Vignati, Vienna, Austria

Application November 13, 1935, Serial No. 49,454
In Austria November 17, 1934

6 Claims. (Cl. 67—7.1)

My invention relates to lighters, for example, to pocket lighters for cigars or cigarettes, and it is an object of my invention to provide an improved lighter.

- 5 To this end, I provide, in combination with an outer case, and a gas compartment in the case; a casing which projects into the gas compartment and at its lower end has a tube establishing communication between the compartment and the interior of the casing. In the lower end of the casing, I insert a body which has a central bore or gas passage. This bore or passage is widened at its lower end and in the widened portion I place a plurality of superimposed porous elements 15 in which the gas from the tube expands and its pressure is reduced. A plug with a central bore in whose extension a burner pipe is arranged, is screwed into the casing at the upper end thereof and a closing member is arranged between the 20 plug and the body for controlling the opening of the narrower portion of the gas passage in the body. Lastly, I provide means for turning the plug so as to open and close the passage which the closing member controls.
- 25 In the accompanying drawing, a lighter embodying my invention is illustrated more or less diagrammatically by way of example.

In the drawing

Fig. 1 is an axial section showing the important parts of the lighter,

Fig. 2 is a section taken at right angles to the one in Fig. 1, and showing more detail than Fig. 1, including a gas compartment and a sparking wheel,

35 Fig. 3 is a plan view of Fig. 1, and

Fig. 4 is a perspective illustration of a complete lighter.

Referring now to the drawing, 1 is the case of the lighter, and 1^a is a gas compartment in the case. 20 is a lid closing the case at its upper end, 23 is a spring tending to open the lid by turning it about its pivot 24, 25 is a bearing for the pivot, 26 is a sparking wheel on the pivot, 27 is a piece of cerium iron housed in a cylinder projecting downwardly from a bracket 1^b in the case 1, and 28 is a spring urging the piece 27 against the wheel. The lid 20 is normally held in closed position by a hook 21 depending from its lower side and a movable hook 19 which engages the hook 21. When the hook 19 is moved away from the hook 21, as will be described, the spring 23 throws open the lid 20 and at the same time rotates the sparking wheel past the cerium iron so that sparks are emitted to light the gas, as will also be described. 2 is a gas supply tube leading into the

gas casing 3 and a hollow body 4 arranged in the lower part of the casing 3 and containing a plurality of superposed porous elements 5 which are secured by the screw 6. The gas egress takes place through the outlet 7. The gas, which comes from the gas compartment 1^a into the tube 2, passes through the porous elements 5 and loses so much pressure in this way that it may flow through the outlet 7 with a minimum of over atmospheric pressure. The outlet 7 is closed by a 10 closing member 8 of the inset plug 9 which is screwed by its thread into the casing 3. When the inset plug 9 is raised by its turning movement, the closing member 8 is lifted from the opening 7 and the gas is enabled to pass through 15 the opening 7 into the lateral channel 10 and from the latter to the gas outlet bore 11 and to the space of consumption 22. The spring 12 causes the inset plug 9 to turn back into its shutting position. The inset plug 9 is integral with a 20 cigarette wheel 14 provided with teeth 15. On the head of the cigarette lighter there is arranged a disk 16 which is provided with a pin 17 which is adapted to engage between the teeth 15 of the wheel 14. The disk 16 can be turned by a 25 lever 18. The said disk is also connected to the movable hook 19 already referred to by means of a sleeve 16^a mounted to turn in the bracket 1^b.

The lighter operates as follows:

When the lever 18 is turned, the pin 17 engages 30 with a tooth of the toothed wheel 14 and the inset plug 9 is turned thereby in the upward direction so that the gas may pass through the bore 11 to the opening 22. At the same time the lid 20 of the lighter opens as it is no longer kept by the 35 hook 19. The opening of the lid of the lighter turns the sparking wheel 26 and thereby causes the production of sparks. The gas flowing out from the opening 22 is ignited by the sparks. The quantity of escaping gas increases upon further 40 turning of the lever 18 so that the flame is regulated according to the position of the lever 18. The spring 12 draws the lever 18 into its original shutting position so that, if the lever 18 is released, the gas supply is stopped automatically. 45

The spring 12 also keeps the closing member 8 on the upper end of the body 4 so that gas will not escape if the lighter is subjected to shock. The flow of gas cannot take place earlier than after the power of said spring has been overcome 50 by the actuation of the lever 18 and of the pin 17.

I claim:

1. In a lighter, comprising an outer case, a gas compartment in said case, a casing projecting into said compartment, a tube at the lower end 55

- of said casing establishing communication between said compartment and the interior of said casing, a body in the lower end of said casing having a central bore widened at its lower end, a plurality of superposed porous elements in the widened end of said bore, a plug screwed into the upper end of said casing and having a central bore, a burner tube forming an extension of said bore, a closing member between said plug and said body, said member adapted to be pressed against the upper side of said body to close the bore thereof, and operating means for turning said plug to lift said closing member off said body to control the passage of gas from said compartment to said burner.
2. In a lighter as specified in claim 1 a spring between the plug and the casing adapted to return said plug into its initial position and close the bore in said body.
3. In a lighter as specified in claim 1 the operating means, comprising a small toothed wheel fixed on the upper end of the plug, a pin engaging the teeth of said wheel to rotate said plug, and a disc carrying said pin on a lever rigidly connected with said disc and projecting through a slot in said outer case, said lever adapted to rotate said disc to turn said plug through the intermediary of said pin engaging in said toothed wheel.
4. In a lighter as specified in claim 1 the operating means, comprising a small toothed wheel fixed on the upper end of the plug, a pin engaging the teeth of said wheel to rotate said plug, a disc carrying said pin on a lever rigidly connected with said disc and projecting through a slot in said outer case, said lever adapted to rotate said disc to turn said plug through the

intermediary of said pin engaging in said toothed wheel, an automatically opening lid hingedly mounted on said outer case, and a catch carried by said disc adapted to maintain said lid in closed position and to disengage from said lid on the rotation of said disc.

5. In a lighter as specified in claim 1 the operating means, comprising a small toothed wheel fixed on the upper end of the plug, a pin engaging the teeth of said wheel to rotate said plug, a disc carrying said pin and a lever rigidly connected with said disc and projecting through a slot in said outer case, said lever adapted to rotate said disc to turn said plug through the intermediary of said pin engaging in said toothed wheel, an automatically opening lid hingedly mounted on said outer case, a catch carried by said disc adapted to maintain said lid in closed position and to disengage from said lid on the rotation of said disc, and a spark producing device being operatively connected to said lid and adapted to be actuated by the opening of said lid to ignite the gas passing out of the burner.

6. In a lighter as specified in claim 1 the operating means, comprising a small toothed wheel fixed on the upper end of the plug, a pin engaging the teeth of said wheel to rotate said plug, a disc carrying said pin on a lever rigidly connected with said disc and projecting through a slot in said outer case, said lever adapted to rotate said disc to turn said plug through the intermediary of said pin engaging in said toothed wheel, and a stopping device adapted to arrest said lever in any desired position to regulate the outflow of gas through the burner.

OTTO REICH.
